UNITED STATES PATENT OFFICE

MAURICE LEE WARNER, OF DOVER, OHIO, ASSIGNOR TO DOVER MANUFACTURING COMPANY, OF DOVER, OHIO, A CORPORATION OF OHIO

FUSE

Application filed June 13, 1928. Serial No. 284,899.

This invention relates to improvements in fuses. The fuse herein disclosed is particularly adapted for use in connection with electrical appliances such as percolators or the like but has other utility as will be obvious from the disclosure.

It is the object of the invention to provide a novel and simple form of fusible element and mounting therefor which can be easily and economically manufactured and which is adapted for ready manipulation and replacement by inexperienced persons.

More specifically stated, it is my purpose to provide a fusible element in the form of the shank of a spool, the spool heads being made of brass or some other material adapted to give better contact than is possible in the use of the fusible material. This spool is adapted to be inserted to operate a cap between two resiliently separable spring arms in series with the current supplied to a heating element so that if the spool melts the arms will separate and the current will be interrupted. Such a device as this may be made to operate whenever a percolator or like heating appliance boils dry, thereby saving much damage to the percolator. Because of the fact that the circumstances which give rise to the melting of the fuse may occur frequently, it is a purpose of this invention to make the fuse very easily replaceable and this is accomplished by the design of the spool-shaped fuse member and by the springs which are formed with slots readily adapted to receive the shank of the spool.

In the drawings,—

Figure 1 is a side elevation of a percolator having its skirt portion broken away to expose the electrical contact mechanism;

Figure 2 is a plan view of the bottom of the percolator shown in Figure 1 illustrating the application of a fuse and fuse mounting of this invention to the contact mechanism;

Figure 3 is an enlarged detail partially in axial section of the support for the fuse mounting on the contact mechanism;

Figure 4 is an enlarged detail in side elevation of one of the resilient fuse mounting arms;

Figure 5 is an enlarged detail in axial section of the fuse unit.

Like parts are identified by similar reference characters throughout the several views.

The percolator comprises a receptacle 6 having a skirt portion 7 spanned by a bar 8 from which the pressure screws 9 support heating element 10. A mounting plate 11 attached to the heating element is provided with a depending bracket 12 in which the terminal posts 15 and 16 are supported for registry with the plug receiving member 17.

Each of the terminal posts 15 and 16 is insulated from the bracket member 12 by suitable di-electric washers 18. Terminal post 16 may be connected directly to the heating element by means of a conductor 19, as shown in Fig. 2. Terminal post 15 carries the fuse and fuse mounting hereinafter to be described.

The fuse mounting comprises a pair of spaced spring arms 20 and 21 which tend resiliently to separate and to assume the positions indicated by the dotted lines in Fig. 2. Spring arm 20 is mounted directly upon the terminal post 15 on the inside of bracket 12, as shown in Fig. 3. A di-electric spacer 23 is provided at 24 with a boss upon which spring arm 21 is mounted. The conducting lead 25 to the heating element is in direct contact with spring arm 21 and is held in pressure engagement therewith by means of nut 26 and di-electric washer 27. It will be obvious, therefore, that spring arms 20 and 21 are insulated from each other and are connected respectively with the source of current supply and with the heating element.

During normal operation of the device, an electrical connection is established between spring arms 20 and 21 by means of the fuse element shown in detail in Fig. 5. As suggested above, this element comprises two brass or copper heads 30 counter-sunk at 31. The fusible material is made in the form of a shank or spindle 32 which connects heads 30 and is riveted in the counter-sunk recesses 31, as shown in Fig. 5. Each of the spring arms 20 and 21 is provided at 33 with a downwardly and rearwardly opening slot into which the shank or spindle portion 32 of the spool-

shaped fuse element is receivable. The length of such shank or spindle portion is such that when the fuse is in place the spring arms 20 and 21 will be substantially parallel and are thereby enabled to make face contact with the heads 30 of the fuse element. The fact that such heads are of some excellent conducting material such as brass, bronze, or copper, insures the establishment of a good contact through the fuse device. It is found that the soft fusible material does not ordinarily make an adequate contact.

10 The fuse is secured against displacement from its proper position not only by the downward direction and by the curvature of the slots 33 but also by means of the spring tension of arms 20 and 21 which is customarily exerted against the heads 30 to maintain a frictional resistance against displacement.

20 Upon such occasions as the fuse requires renewal, however, it is an extremely easy matter to press the spring arms 20 and 21 together and to introduce a new fuse element into the slots 33 thereof.

25 It may be noted that the fact that the fuse mounting subjects the fuse to tension rather than to compression has been found to result in great dependability of operation. There is little or no possibility that any part of the 30 fuse may lodge between the mounting arms in such a way as to maintain a current after the device becomes overheated. It is found that the temperatures at which this device will operate may be predetermined with considerable accuracy so that in any case in 35 which the receptacle 6 is empty while current is supplied to the terminal posts 15 and 16 the resulting heat will, with certainty, melt the link 32 to break the electrical connection 40 to the heating element.

The spring arms 20 and 21 project from the mounting near the center of the percolator to a position such that the fuse is held in close proximity to the skirt portion 7 thereof. It 45 is found that when a percolator boils dry and becomes over-heated the temperature of the skirt portion will rise very rapidly and due to the location of the fuse in this device it will be more sensitive to such rise of temperature 50 than would be the case if it were located elsewhere.

I claim:

1. In a device of the character described, the combination with a mounting plate and 55 terminal posts thereon, of a heating element, a receptacle above said element provided with a skirt surrounding said element and mounting plate, and a pair of arms supported from said mounting plate and projecting toward 60 a portion of said skirt whereby to be adapted to receive heat therefrom, and a fusible link connecting said arms adjacent said skirt, one of said arms being in electrical connection with said heating element and the other 65 of said arms being in electrical connection

with one of said posts and insulated from said first mentioned arm save for said link.

2. In a device of the character described, the combination with a receptacle having a skirt portion subject to an increase of heat 70 when said receptacle is overheated, a heating element beneath said receptacle and within said skirt, a terminal post and a fuse mounting connected in series between said terminal post and element, and comprising a pair of 75 arms projecting from said post toward said skirt and a fusible link replaceably carried by said arms adjacent said skirt.

3. In a device of the character described, the combination with a receptacle having a 80 skirt portion subject to an increase of heat when said receptacle is overheated, a heating element beneath said receptacle and within said skirt, a terminal post and a fuse mounting connected in series between said terminal 85 post and element, and comprising a pair of arms projecting toward said skirt, and a fusible link replaceably carried by said arms adjacent said skirt, said arms being resiliently separable and said link being provided 90 with heads adapted normally to restrain said arms against separation.

4. In a device of the character described, the combination with a receptacle having a 95 skirt portion subject to an increase of heat when said receptacle is overheated, a heating element beneath said receptacle and within said skirt, a terminal post and a fuse mounting connected in series between said terminal post and element, and comprising 100 a pair of arms projecting toward said skirt, and a fusible link replaceably carried by said arms adjacent said skirt, said arms being supported in mutually spaced relation at their inner ends and resiliently separable at their 105 outer ends, and said link being provided with non-fusible heads exteriorly contacting with said arms and adapted to restrain them against separation at their outer ends.

5. In a device of the character described, 110 the combination with a receptacle having a skirt portion subject to an increase of heat when said receptacle is overheated, a heating element beneath said receptacle and within 115 said skirt, a terminal post, and a fuse mounting connected in series between said terminal post and element, and comprising a pair of arms projecting toward said skirt, and a fusible link replaceably carried by said 120 arms adjacent said skirt, said arms being resiliently separable at the ends adjacent the skirt and being provided with upwardly opening slots adjacent said ends, and said link comprising a spool-shaped element having relatively non-fusible heads engaging 125 said arms, and a shank portion receivable in said slots and provided with a fusible part.

MAURICE LEE WARNER.
